MULTIPURPOSE BRACKET

Milton Koegler and Samuel Silverstein,
Jacksonville, Fla.

Application April 22, 1949, Serial No. 88,932

1 Claim. (Cl. 248—264)

1

This invention relates to a bracket for supporting window accessories, such as curtains, drapes, or Venetian blinds, and more particularly to a bracket capable of accommodating several of such accessories at the same time.

The primary object of this invention is to provide a bracket which is adapted to support at the same time a variety of window accessories adjacent a window, and which is composed of a minimum of parts and may be cheaply manufactured.

Another object of the invention is to provide a multi-purpose bracket which is capable of supporting a drapery in a plurality of adjustable positions.

A further object of the invention is to provide a multi-purpose bracket which is simply installed, and which is mountable on any conventional window frame in a plurality of positions thereon.

Other and further objects and advantages will become apparent from the following detailed description of the drawing, wherein:

Figure 1 is a side elevational view of the device of this invention mounted on a conventional window frame and supporting a variety of window accessories;

Figure 2 is a view in cross-section of the device taken on the line 2—2 of Figure 1, the dotted lines indicating the position of the facia board holder means mounting the facia board thereon and the full lines indicating the position of the facia board holder means with the facia board mounted thereon;

Figure 3 is a top plan view of the device taken along the line 3—3 of Figure 2, showing the drapery rod-supporting means in various positions of adjustment, the full lines indicating one position of adjustment and the dotted lines indicating another position of adjustment;

Figure 4 is an exploded elevational view in perspective of the device, showing the relative arrangement of the parts;

Figure 5 is a top plan view in cross-section taken along the line 5—5 of Figure 4;

Figure 6 is a side elevational view in cross-section taken along the line 6—6 of Figure 4.

In the drawings, wherein like reference numerals refer to identical parts, the device of this invention comprises a flat bracket body 8, Figures 4 to 6, inclusive, having a drapery rod-supporting means 9 and a facia board holder means 10 carried adjacent one end of the body 8, there being a head rail-supporting means 11 secured

to the body 8 intermediate the ends of the latter.

The body 8 is provided with a wing portion 12 adjacent one end thereof and flange portion 13 adjacent the opposite end. The wing portion 12 is provided with a bearing 13'. The flange portion 13 is suitably apertured at 14 for securement to a conventional window frame 15, as shown in Figure 1.

10 The bearing 13' of the wing portion 12 pivotally carries the drapery rod-supporting means 9. The drapery rod-supporting means 9 comprises a hinge plate 16 having bearings 17 and 17' disposed in alignment with the bearing 13' and operatively secured to the latter by a pin 18 which passes the aligned bearings 17, 13' and 17'. The means 9 further includes a cover plate 19 which is adjustably secured by screws 20 in superposed relation with respect to the hinge plate 16 and spaced therefrom to supportingly clamp a portion of a drapery rod 21 therebetween. The means 9 is thus mounted for a limited pivotal movement about a vertical axis, as clearly shown by the dotted lines in Figure 3.

25 Adjacent the wing portion 12 and carried by the body 8 is the facia board holder means 10, the latter means comprising a holder 22 disposed in superposed relation with respect to said body 8. The holder 22 is of L-shaped cross-section 30 and is provided with a back plate 23 which is pivotally attached at 24' to the body 8 to permit a limited swinging movement of the holder element 22 about a horizontal axis, as shown in dotted lines in Figure 2. The holder element 22 35 is further provided with a J-shaped lug 24 for the accommodation of an end of a curtain rod 25. To lock the holder element 22 in position on the body 8, the back plate 23 is provided with a locking bump 26 which is engageable with a 40 recess 27 in the body 8.

The head rail-supporting means 11 comprises a U-shaped head rail clip 28. The bight 29 of the U is secured to the body 8, as by riveting. The upper leg 30 of the clip is apertured to permit securement of the bracket body 8 to the horizontal part of the window frame 15, as shown in Figure 2. The lower leg 31 is also apertured to accommodate an end of a head rail 32 of a Venetian blind 33.

50 Thus, a multi-purpose bracket is provided which can accommodate at the same time a variety of accessories for a window frame, as shown in Figure 1. For example, a drapery 34 may be supported on the drapery rod 21 which is clamped in position on the drapery-supporting means 9.

Also, a facia board 35 may be supported by the holder means 10. A curtain 36 may be mounted on the curtain rod 25 carried by the J-shaped lug 24. Furthermore, the head rail clip 28 may support an end of a Venetian blind head rail 32.

We claim:

In a multi-purpose bracket for attachment to a window frame, a vertically-disposed flat bracket body with means at one end thereof for securing it to a window frame, a hinge plate carried by the opposite end of said body and mounted thereon for pivotal movement about a vertical axis, a cover plate adjustably secured in superposed relation with respect to said hinge plate and spaced therefrom to supportingly clamp a portion of a drapery rod therebetween, and a

head rail clip secured to said body intermediate said ends for supporting an end of the head rail carrying a Venetian blind.

MILTON KOEGLER.
SAMUEL SILVERSTEIN.
